UNITED STATES PATENT OFFICE.

CHARLES M. BONHAM, OF NEW YORK, N. Y.

ADJUSTABLE SHOE-BUCKLE FASTENER.

1,092,010.

Specification of Letters Patent. Patented Mar. 31, 1914.

Application filed March 31, 1913. Serial No. 757,848.

To all whom it may concern:

Be it known that I, CHARLES M. BONHAM, a citizen of the United States, and a resident of the city of New York, borough of Manhattan, in the county and State of New York, have invented a new and Improved Adjustable Shoe-Buckle Fastener, of which the following is a full, clear, and exact description.

This invention relates to shoe buckles or ornaments adapted for use particularly in connection with pumps although it is not limited exclusively to this application, and the invention has to do more especially with fastening or attaching devices for buckles or other ornaments.

The invention has for its principal object to provide a fastening or attaching device for buckles which is so designed that the buckle can be fastened to the shoe easily, quickly and securely, and by the use of an ordinary stapling machine so that sewing of the buckle on the shoe as is now necessary is dispensed with, although the present fastener may be sewed to the shoe, if desired.

A further object of the invention is the provision of an attaching base provided with a bendable stem to which the buckle or body of the ornament is secured, the stem being bendable so that the base can be placed in the proper position for enabling a stapling machine to be used for applying the buckle, and when applied or fastened the buckle can be adjusted to the proper position by bending the stem.

Another object is the provision of a single piece attaching base which is of comparatively simple and inexpensive construction adaptable for buckles of various designs.

With such objects in view, and others as will appear as the description proceeds, the invention comprises various novel features of construction and arrangement of parts which will be more fully described herein-after and set forth with particularity in the claims appended hereto.

In the accompanying drawings, which illustrate one embodiment of the invention, and wherein similar reference characters are employed to designate corresponding parts throughout the several views, Figure 1 is a side view of a shoe with the improved buckle applied thereto; Fig. 2 is a perspective view of the buckle fastening or attaching device; Fig. 3 is a perspective view of the rear side of the buckle with the attaching device ap-

plied; Fig. 4 is a sectional view of the buckle secured to the shoe; Fig. 5 is a similar view showing the position of the buckle when the staples are being applied.

Referring to the drawing, A designates a shoe, such as a pump, with a buckle B applied thereto. The buckle is secured to the shoe by an attaching or fastening device which is constructed as shown in Fig. 2, such device comprising a base 1 and an upwardly extending stem 2, disposed at right-angles or approximately so to the base 1. This stem has forwardly-projecting lugs 3 and 4 to which the buckle is secured by soldering or any other suitable manner. The upper lug 3 is formed by bending laterally the extremity of the stem while the lower lug is formed by doubling on itself an intermediate portion of the stem. The base portion 5 of the stem is bendable so that after the buckle is fastened to the shoe the buckle can be adjusted to the desired position.

Before the buckle is secured to the shoe the base 1 is disposed at right-angles to the stem 2, and in applying the buckle the base is placed against the shoe at the required point in the manner shown in Fig. 5. This enables the buckle and shoe to be clamped in an ordinary stapling machine and staples 6 are employed to fasten the buckle in place, the staples 6 being inserted through openings in the base 1. After the buckle is applied to the shoe as shown in Fig. 5 the buckle is pressed backwardly to bend the base 5 of the stem until the buckle is in a position somewhat like Fig. 4, but the angle at which the buckle is placed can be adjusted to suit the fancy of the wearer or to fit the instep of the foot.

With the construction shown it is apparent that the buckle can be easily, quickly and securely applied to the shoe and at the same time the buckle can be adjusted at any desired angle.

From the foregoing description taken in connection with the accompanying drawings, the advantages of the method of operation and of the device shown will be readily understood by those skilled in the art to which the invention appertains, and while I have described the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent

1. The combination of a body of a buckle or ornament, with an attaching device therefor comprising a base, and a stem connected therewith and having its upper end formed into a lug for connection with the said body and having its lower portion doubled laterally to form a lug for connection with said body.

2. A buckle attaching device comprising a single piece of metal formed into a base, a stem rising from the forward edge of the

base, a lug on the upper end of the stem projecting forwardly therefrom, and a second forwardly-projecting lug on the lower portion of the stem, the lower lug being formed by doubling forwardly a portion of the stem and the stem being bendable adjacent the said base.

In testimony whereof I have signed my name to this specification in the presence of two subscribing witnesses,

CHARLES M. BONHAM.
